UNITED STATES PATENT OFFICE.

JOSEPH S. O'BRIEN, OF WESTFIELD, MASSACHUSETTS.

TROLLEY-SHOE.

1,367,920.

Specification of Letters Patent.

Patented Feb. 8, 1921.

Application filed July 3, 1920. Serial No. 393,785.

To all whom it may concern:

Be it known that I, JOSEPH S. O'BRIEN, a citizen of the United States of America, and a resident of Westfield, in the county 5 of Hampden and State of Massachusetts, have invented a new and useful Trolley-Shoe, of which the following is a specification.

My invention relates to improvements in 10 non-rotary devices carried at the upper ends of trolley poles to slide under and in contact with the trolley wire, and which are commonly termed "shoes", and consists essentially of a suitable holder or frame that is adapted 15 to be attached to a trolley pole, and a member which is preferably spherical or approximately so, and is provided with a plurality or multiplicity of trolley-wire-receiving grooves, in the periphery or sides there- 20 of, designed to serve individually as guides for said member when in contact with a trolley wire, said member being supported in and carried by said frame, together with locking means for said member, whereby 25 the latter is held stationary in said frame, but may be released to enable the same to be adjusted in or removed from the frame, all as hereinafter set forth.

Actual practice and experience have dem- 30 onstrated the fact that a non-rotary mem- ber or shoe, at the end of a trolley pole for contact with the trolley wire, outlasts a con- siderable number of rotary members or 35 wheels which have heretofore been very ex- tensively and commonly used, and the primary object of my invention is to provide a trolley shoe that, by reason of its peculi- 40 ar construction which comprises or in which is included a plurality or multiplic- ity of receiving or engaging parts for the trolley wire, is capable of adjustment so that, when one such part is worn away suf- 45 ficiently to be of no further use, another can be presented or located in operative posi- tion and which shoe therefore has a very 50 much longer life than the ordinary shoe. A great saving in expense thus accrues, more especially since my shoe is simple and com- paratively inexpensive to construct, operate, 55 and maintain.

Another object is to provide a shoe of this character that can be easily and quickly adjusted to bring into position for contact with the trolley wire a fresh and unworn 55 part or grooved portion, and which can be taken apart and put together again readily

and conveniently. The purpose of and need for this last advantage will appear more clearly hereinafter.

Other objects and advantages will appear 60 in the course of the following description.

I attain the objects and secure the ad- vantages of my invention by the means 65 illustrated in the accompanying drawings, in which—

Figure 1 is a top plan of a trolley shoe which embodies a practical form of my in- 70 vention; Fig. 2, a side elevation of said shoe; Fig. 3, what may be termed an end elevation of the shoe as viewed from the right of Figs. 1 and 2; Fig. 4, an enlarged, 75 central, horizontal section through the wire- engaging element or shoe proper, taken on lines 4—4, in Fig. 2, and, Fig. 5, an en- larged, central, vertical section through said wire-engaging element, on lines 5—5, Fig. 2.

The last two views are taken with the wire-engaging element disposed as it is in 80 the other views.

Similar reference characters designate 85 similar parts throughout the several views.

In the embodiment of my invention pre- 90 sented herewith the same comprises, as will be seen upon referring to the drawings, a holder or frame 1 which is provided at one 95 end with a downwardly and outwardly oblique socket 2, a spherical member 3 which is the element that comes into direct contact with the trolley wire, and which may be termed a spherical shoe, a bolt 6 that constitutes a shaft or spindle upon which said spherical shoe is mounted, the latter being received in said frame, a nut 7 for said bolt, and a lock-screw 8 to hold said spherical shoe in place or prevent the same from rotating on said spindle after ad- justment of the shoe has been effected.

The frame 1 has flaring ears or wings 9—9 at the top to serve as guides to direct 100 the device into place in contact with the trolley wire, such wings being not unlike similar members on other trolley-shoe de- vices at the upper ends of trolley poles, both struc- turally and functionally.

The socket 2 is designed to receive therein 105 the upper terminal of a trolley pole, and it is by means of this socket that the device is attached to such pole. There is an opening 110 through the frame 1 and the sides there- of, which opening is large enough to admit the spherical shoe 3. The bolt or spindle 6

is received in suitable openings made in the centers of the end portions of the frame 1 in line with the horizontal diameter of the opening 10, and said spindle is held in place 5 longitudinally by its head and the nut 7, as clearly appears, and may be withdrawn from said frame upon the removal of said nut. The lock-screw 8 is tapped into and through the periphery of the frame 1 at a 10 convenient point, and extends into the opening 10, the head of said screw being accessible from the outside of said frame. The frame 1 is provided with exterior reinforcements, as represented at 11—11, to accommodate the lock-screw. 15

The spherical shoe 3 has intersecting, right-angular passages 12 and 13 therein, either of which passages is adapted to receive the spindle 6. In the periphery of the 20 spherical shoe 3, arranged concentrically with the passage 12, is a series of grooves 14, there being twelve such grooves in the present case. And arranged in the periphery of the spherical shoe 3, concentric with the passage 13, are two sets or series of 25 grooves 15, there being three such grooves at and adjacent to each end of the passage 12 in the present case. The grooves 14 are parallel with the passage 12, and the grooves 30 15 are parallel with the passage 13. The grooves 14 and 15 are all practically alike in shape and dimensions, just as the passages 12 and 13 are alike. Each groove or grooved part 14 (or 15) is of a size and 35 shape suitable for the reception of and engagement with a trolley wire, as 16 in Fig. 3, and of sliding along in contact with such wire.

When the spherical shoe 3 is mounted in 40 the frame 1 with the spindle 6 extending through the passage 12, the grooves 14 are in operative position, or, rather, one of such grooves is in such position, and the others are adapted to be moved at any time into 45 such position. The uppermost groove or grooved part 14 receives the trolley wire 16 and slides along the same. After the aforesaid uppermost groove or grooved part has become worn to a sufficient extent, a 50 fresh or unworn groove or grooved part 14 is presented beneath the wire, the spherical shoe 3 being partially rotated on the spindle 6 to the extent necessary to locate in operative position the fresh groove. After all of 55 the grooves 14 have become incapacitated for further use, the nut 7 is removed from the spindle 6, the latter is withdrawn from the spherical shoe 3, the latter is turned to present to said spindle the passage 13, and 60 said spindle is thrust through said passage and into place again in the frame and secured with said nut. Now the grooves or grooved parts 15 are in position for use in place of the grooves or grooved parts 14, 65 and each of said grooved parts 15 is or may

be utilized for engagement with the wire 16 just as was each of the grooved parts 14. Until all of the grooved parts 14 and 15 have become practically useless by reason of wear the spherical shoe 3 is serviceable, 70 wherefore it is clear that this shoe will endure a long time and outlast a very large number of ordinary trolley shoes, and still a greater number of trolley wheels.

The lock-screw 8 is turned inwardly to 75 engage with its inner end the spherical shoe 3, after said shoe has been adjusted for the location of any of its grooves 14 or 15 in receiving and operating position beneath the wire 16. When it is desired to rotate 80 the spherical shoe 3 on the spindle 6, or to remove said shoe from said spindle for any purpose, it is first necessary to turn the lock-screw 8 outwardly a sufficient distance to clear said shoe.

When the spherical shoe 3 is entirely worn out, another can be substituted therefor in the holder.

More or less change in the shape, size, 90 construction and arrangement of some or all of the parts of this device may be made without departing from the spirit of my invention or exceeding the scope of what is claimed.

What I claim as my invention, and desire 95 to secure by Letters Patent, is—

1. A trolley shoe comprising an approximately spherical member having therein a plurality of peripheral trolley-wire-receiving grooves, and means to support said member at the upper end of a trolley pole. 100

2. A trolley shoe comprising an approximately spherical member having therein pluralities of peripheral trolley-wire-receiving grooves arranged concentrically with two 105 axes of said member which are at right-angles to each other, and means to support said member at the upper end of a trolley pole.

3. A trolley shoe comprising a member 110 having two axes at right-angles to each other, and also having in the sides thereof pluralities of trolley-wire-receiving grooves arranged adjacent to the ends of said axes, and means to support said member at the 115 upper end of a trolley pole.

4. The combination, in a trolley shoe, with a holder adapted to be connected with the upper end of a trolley pole, and provided with supporting means, of a member having in the sides thereof a plurality of trolley-wire-receiving grooves, said holder having an opening therein to receive said grooved member, and the latter being adjustably mounted on said supporting means. 120 125

5. The combination, in a trolley shoe, with a holder adapted to be connected with the upper end of a trolley pole, and provided with supporting means, of a member having in the sides thereof a plurality of trolley- 130

wire-receiving grooves, said holder having an opening therein to receive said grooved member, and the latter being mounted on said supporting means, and means to lock 5 said grooved member in place on said supporting means.

6. The combination, in a trolley shoe, with a holder adapted to be connected with the upper end of a trolley pole, and provided with supporting means, of a member having in the sides thereof a plurality of trolley-wire-receiving grooves, said holder having an opening therein to receive said grooved member, and the latter being mounted 10 15 end on said supporting means, and a lock-screw arranged in said holder to engage said grooved member and hold the same against rotation.

7. The combination, in a trolley shoe, with 20 a frame provided at the top with guide wings, and further provided with a trolley-pole-engaging member, and a spindle in said frame, of a member having in the sides a plurality of trolley-wire-receiving grooves, 25 and also having axial passages at right-angles to each other to receive said spindle, said frame having an opening therein to re-

ceive said grooved member, and releasable means to prevent said grooved member from rotating on said spindle. 30

8. The combination, in a trolley shoe, with a frame provided at the top with guide wings, and further provided with a trolley-pole-engaging member, and a spindle in said frame, of a member having in the sides a 35 plurality of trolley-wire-receiving grooves, and also having axial passages at right-angles to each other to receive said spindle, said frame having an opening therein to receive said grooved member, and a lock-screw 40 tapped into said frame and adapted to engage said grooved member to hold the same against rotation.

9. A trolley shoe comprising a member having in the sides thereof a plurality of 45 trolley-wire-receiving grooves arranged approximately parallel with the axis of said member, and means to support said member for adjustment at the upper end of a trolley pole.
